UNITED STATES PATENT OFFICE.

THOMAS H. BRIGG, OF GODSTONE, ENGLAND.

RAILWAY-LOCOMOTIVE.

1,027,810.

Specification of Letters Patent.

Patented May 28, 1912.

Application filed April 18, 1912. Serial No. 691,566.

To all whom it may concern:

Be it known that I, THOMAS H. BRIGG, a subject of the King of Great Britain and Ireland, residing at Godstone, in the county 5 of Surrey, England, have invented new and useful Improvements in Railway-Locomotives, of which the following is a specification.

My invention relates to improvements in 10 the design and construction of railway locomotives in conjunction with their tenders and interposed cabs, their suspension, and propulsion; and the objects of my improvements are, first, to afford far greater safety 15 to the general traveling public; and, second, to effect far greater economy and efficiency in the performance of their work especially when negotiating curves and climbing gradients than can possibly be effected by the 20 imperfect and dangerous methods now in use. I attain these objects by a locomotive boiler, tender and cab interposed between them, connected to each other and to a supporting frame so as to form a long rigid 25 and infrangible structure providing a long flexible wheel base, having a plurality of pivotal driving and supporting trucks located at or near the extremities of said structure as illustrated in Figure 2. of the 30 accompanying drawings, in which—

Fig. 1, is a side elevation of a modern British locomotive and detachable tender, having a total weight of 240,632 lbs. with a tractive capacity of only 14,220 lbs. Fig. 35 2, is a side elevation illustrating the improved design and construction embodying the same boiler and same capacity of tender as in Fig. 1, but now giving a tractive capacity of 56,133 lbs. Fig. 3, is a side elevation 40 of a modern British tank-engine weighing 138,880 lbs. with only 80,640 lbs. bearing upon its 8'-3" rigid wheel base. Fig. 4, is a side elevation of the same boiler as shown in Fig. 3, with a slightly deeper 45 and longer tender, with the forward end of the boiler resting upon a long based bolster. Fig. 5, is a side elevation of an American tank engine with a rigid wheel base α of about .9 feet, with no fewer than 50 8 free supporting wheels. Fig. 6, is a side elevation of the same boiler as shown in

Fig. 5, with a slightly longer and higher tender; and mounted upon a flexible wheel base. Fig. 7, is a graphic diagram showing a lateral outward thrust of 9,000 lbs. for 55 every 42,500 lbs. of buckling force, with center bumpers. Fig. 8, is a graphic diagram showing only 4,500 lbs. of a lateral outward angle with side bumpers, with the same buckling force as in Fig. 7. Fig. 9, 60 65 is a graphic diagram showing two cars at a given angle with center bumpers, fixed to ends of cars. Fig. 10, is a graphic diagram showing two cars at the same angle as in Fig. 9, with center bumpers fixed to the 70 pivotal trucks.

Fig. 1, shows the ordinary suspension of a modern British 4-coupled locomotive and detached tender. The former weighing 149,632 lbs. while the latter weighs 90,496 70 lbs. or a total of 240,128 lbs. of which only 60,580 lbs. are carried upon the two sets of driving wheels X X, forming a rigid wheel base of .7 feet 3 inches. Well now, since the measure of the co-efficient of friction, 75 between the driving wheels and the rails is the measure of the tractive capacity of the locomotive; and, that the friction is dependent upon (a) the weight upon the driving wheels, and (b) the condition of the rail 80 surface, then, if we take this factor to represent 4.26 of the weight on the drivers, we shall find that the tractive capacity of the locomotive and tender Fig. 1. is 14,220 lbs. less that amount which is due to the automatic transference of weight from the drivers X X, to the free wheels Y, whereas in 85 Fig. 2. the total weight of the said 240,128 lbs. is carried upon pivotal driving trucks D D, by so designing and constructing the 90 boiler, and tender (of full capacity) with interposing cab between them, connected to each other and to a supporting frame in any suitable manner to resist vertical strains and so as to form the said long rigid and 95 infrangible structure providing an unusually long flexible wheel base, having a plurality of said driving trucks D D located at or near the extremities of said structure, we now find, under these improved conditions, that the said 240,128 lbs. 100 so compiled, carried, and driven, will yield

a tractive capacity of no less than 56,133 lbs. as against only 14,220 lbs. when detachably compiled, carried and driven as in Fig. 1. It therefore follows that a locomotive 5 weighing only 61,000 lbs. properly designed and constructed, as described, would be effective in hauling the same load as one weighing 240,128 lbs. designed and constructed as set forth in Fig. 1. The wheel 10 base of the locomotive should be nearly equal in length to that of the coaches. Just as large wheels run more easily over rough roads from the fact that they bridge over many hollow parts instead of sinking 15 deeper into them, so it is with a long flexible wheel base of a locomotive when negotiating a curve; it, practically, secures the same mechanical advantages by bridging over, to a material degree, the hollows and 20 sharpness of all dangerous curves. Then again, the center of gravity of the mass load, of the boiler, and tender with interposed cab, does not travel either so far or so fast when negotiating curves on a long flexible 25 wheel base as it would travel on a short base. By discarding the detached tender, one of the greatest mechanical defects which has probably caused 8 out of every 10 derailments, broken rails, rail-spreading 30 and track-jumping accidents, viz. the excessive over-lap of the rear extremity of the locomotive, over that of the front end of the tender together with the unsatisfactory method of connecting the engine and tender, 35 has been entirely removed by the new method of construction and suspension as heretofore described.

Fig. 3. is an elevation of a modern British tank engine driven by two sets of driving 40 wheels X X, forming a rigid wheel base 8 feet 3 inches long. The total wheel base being 27 feet. Although this boiler and tender forms one rigid structure it is not mounted upon a flexible wheel base, or upon 45 pivotal driving trucks. And if it were so mounted it would not make an efficient locomotive from the fact that it would not run so steadily, so easily, or so safely on curves due to the center of gravity of the mass load 50 above the trucks traveling nearly the full radius of every curve instead of bridging them over, to a very material degree as would be the case with a much longer wheel base.

55 Fig. 4. is an illustration of the preceding boiler, and tender with its short rigid frame-work mounted upon pivotal trucks to show that in order to get sufficient weight upon the rear driving truck D, it would have to be 60 moved considerably farther forward than the position shown which is already too far forward to avoid lateral strains being effected upon the next adjoining coach when entering a curve, and resisting buckling forces 65 on a curve. To secure anything approach-

ing economic conditions it would be necessary to make the bolster J J, with a much more forwardly extended base, as indicated at a in Figs. 2 and 4 and a much longer frame-work in order to secure efficiency and 70 safety. To increase the length of wheel base is to, practically widen it when on a curve, therefore, to avoid undue lateral thrusts against the outside rails it is essential that the center of gravity of the locomotive 75 should be such that the resultant obliquely downward thrust upon the outside rail should be at such an angle as not to cause a shearing force at the spikes. Hence the importance of lifting the center of gravity of 80 that part forming the tender which has hitherto been too low with disastrous results in the form of rail-breaking and spreading and the like.

Fig. 5. is an American tank engine which, 85 although it lends itself somewhat more favorably to the adaptation of the new-suspension, yet, the length of rigid frame-work is not by any means so long as it should be.

Fig. 6. shows a slightly extended and more 90 elevated tender; also, it shows the forward end of the boiler resting in, and fixed to, a long based bolster J, suitably attached to the extended frame-work, as is also shown in Figs. 2 and 4. The bolster J, is to give a 95 more rigid formation to the boiler and frame-work and to secure a firm bearing for the forward truck. Notwithstanding all this, it cannot be said that the length of wheel base is anything like what it should 100 be to secure the maximum of efficiency and safety in the negotiation of curves. In the case of driving trucks it might be found of advantage to use a free supporting wheel E merely for steadyng purposes, with very 105 little weight upon it. It is important that both the driving, and all free wheeled, trucks should be fitted with central or side bumpers; and that the said bumpers shall form part of the rigid frame-work of the 110 said trucks; and not to form part of the mechanism of the frame-work of the locomotive, the tender, or of the coaches as heretofore from the fact that upon a resolution of the forces as set forth in the graphic diagrams, Figs. 7, 8, 9, and 10, it is made manifestly clear that the rail-spreading, rail-breaking, and track jumping forces are very 115 much greater and more dangerous in case of bumpers which are fitted to the centers of the rigid frame-work of the locomotive, the tender, or the coaches, than if the said bumpers were fitted to the centers and forming part of the rigid frame-work of the driving and free wheeled trucks. In verification of 120 this statement it is deemed essential that an explanation be given as to how these forces are arrived at. Therefore, inasmuch as Figs. 9 and 10 are to a larger scale it might suffice 125 to explain these two with passing reference 130

to Figs. 7, and 8, to account for their slight dissimilarity to meet the dissimilar conditions.

Fig. 9. It is important to point out that this figure represents the plan view of the coupled ends of two coaches anywhere between the locomotive and the last coach—not forming the latter; because the forces exerted upon the first and the last vehicles are very different indeed when negotiating a curve with the brakes applied. While the first and the last vehicles tend to be spun upon their wheel base, it is note-worthy that all intermediate vehicles experience such forces as tend to throw both their ends over the off-side rails simultaneously. The spinning tendency of the locomotive with a short rigid wheel base is a most dangerous feature from the fact immediately the brake is applied on a curve the buckling forces are immensely intensified by the said spinning tendency to twist and lock the short wheel base between the rails thus setting up enormously increased buckling forces which are capable of bending or breaking any rail ever made. These forces do not take place in any other part of the train. Let points 1, 2, 3 and 4, represent the four wheels and axles of one truck of which C is the pivotal pin. In like manner let points 5, 6, 7 and 8 represent the four wheels and two axles of another truck of which D is the pivotal pin. These said trucks are upon the two dotted rails A B and E G, with the ends of the coaches indicated by the numerals 9 10 11 and 12 in the first coach while those of 13 14 15 and 16 indicate the end of the second coach. Point F is the center pin of the American combined coupler and bumper which forms a part of the over-lapping ends of the rigid frame-work of the main body of each coach. Therefore, if we now project the center lines F C E, and F D G, and set off 50,000 lbs. down F E, cutting at H, and 50,000 lbs. down F G, cutting at I, then F H and F I will form two sides of the parallelogram H F I J, the diagonal J F will represent the resultant direction and magnitude (45,250 lbs.) of lateral thrust at the outer rail for every 50,000 lbs. of buckling force through E F and G F.

Fig. 10, however, with the bumpers fitted to the frame-work of the trucks instead of to the frame-work of the coaches we find a very extraordinary reduction of the lateral thrust to result from this method of attaching the bumpers as aforesaid (to the trucks). The reduction is accounted for in this way: The curve, the wheels, and axles, together with the bodies of the coaches shall hold precisely the same relative positions with each other as in Fig. 9. But as the two dotted lines Q 11, and R 15, now indicate the ends of the two trucks with H representing the ordinary American coupling and

bumper, we must proceed to resolve the new forces by again projecting the center lines of the coaches viz. E C, and G D intersecting at F. The bumpers, however, are no longer at F but at H; therefore, inasmuch as H has become the center of moments we must resolve the component and resultant forces at this point; and we must proceed as follows: From H project the line H K which shall be equal to and parallel with I F (in Fig. 9.) which gives us one component force at H. Before we can know what the second component is, or its direction we must draw a line to, and at right-angles with, the direction of force through G F, giving us H I, which forms one arm of a lever constituted by the truck whose pivot is at point D. The second arm of the lever constituted by the truck is H D. Since H I equals 10 and H D equals 32, then, as 32:10::50,000 lbs. equals 15,625 lbs. at D, in the direction D J, which now gives us the second component at H. Therefore, draw H M parallel with D J and measure down 15,625 lbs. cutting at M. From M draw M L parallel with H K, we thus complete the parallelogram H K L M the diagonal H L will now give us the direction and magnitude of the forces acting at H. Now, since the forces at H are opposite and equal from both trucks we must now project the line L H (continued indefinitely) down which cut off H O equal to H L which now gives us one side of the desired parallelogram. The other side is easily obtained from the fact that the forces are opposite and equal. Therefore, instead of repeating the above process to find that which we already know, we need only draw H N through C equal in length to H O, and complete the parallelogram H N P O, then the diagonal P H (14,000 lbs.) will equal the lateral thrust against the outer rail as compared with 45,250 lbs. in Fig. 9. The advantage, therefore, of truck fitted bumpers in the mitigation of derailing forces is one not to be overlooked, or in any way to be disregarded.

Figs. 7 and 8. In reference to these it should be noted that there are no vehicles crowding in front or at the rear of the two coaches shown. This fact accounts for the second arm of the lever constituted by the body of the coach being measured from point 24 to 4, because there are no other external forces pressing at the rear extremities of these coaches to the outer rail. Fig. 7, shows the curved ends of the coaches butting against each other, and even then there is shown to be just double the amount of rail-spreading and rail-breaking force against the outside rail by the resultant thrust represented by the diagonal A 24, of the parallelogram A, 2, 24, 4, which equals 9,000 lbs. for every 42,500 lbs. at right-angles with the

radial lines D C and F E. Whereas in Fig. 8, where side bumpers are used—as in England and on the continent—the lateral or diagonal outward thrust is reduced to A 24, which in this case only represents 4,500 lbs. as against 9,000 lbs. in the previous example.

The assumed 50,000 lbs. of crowding force in the above example is, of course, insignificantly small as compared with the enormous forces set up by a rapidly moving train. If the force should be a tractive, instead of a crowding, one; then, every inside truck-wheel except the leaders and off side front driving wheel; and, the off side wheels of the rear truck, will be in forcible contact with the inside rail. Therefore, no outside rail could ever be broken by any other wheels than the leaders of the locomotive in which case the locomotive would be the first to leave the track. No other vehicle could possibly leave the outside rail, in an outward direction when the locomotive is in traction on a curve, except the leading wheels of the tender which is closely coupled to an engine with an unreasonably long overlap which will cause the leading wheels of the tender to be violently thrown with terrific lateral force against the outside rail especially when the locomotive has just made the curve and the tender entering it. The low center of gravity of the tender lends itself an easy prey to the said lateral and buckling forces. This difficulty, however, is entirely overcome by the new design and construction of boiler and tender which shall form one unusually long rigid and infrangible structure substantially as set forth in Fig. 2.

A long wheel base in a locomotive is just as essential for easy negotiation of curves as it is for a horse-drawn vehicle to be fitted with large wheels to negotiate rough and uneven roads. The former bridges over the curves in the rails, while the latter bridges over the hollows and inequalities of the road. The mass of the load of a locomotive does not travel so far or so fast around curves with a long wheel base as it does with a short one. The deduction is that there is greater safety and economy in the former than in the latter.

Having thus described my invention, what I claim is:—

1. In a locomotive a boiler, tender and interposed cab between them, connected to each other and to a supporting frame so as to form an unusually long rigid and infrangible structure providing a long flexible wheel base, having in combination therewith a plurality of pivotal driving and supporting trucks located at or near the extremities of said structure.

2. In a locomotive a boiler, tender and interposed cab between them, connected to each other and to a supporting frame so as

to form a long rigid and infrangible structure providing an unusually long flexible wheel base, having in combination therewith a plurality of pivotal driving and supporting trucks located at or near the extremities of said structure.

3. In a locomotive a boiler, tender and interposed cab between them, connected to each other and to a supporting frame so as to form a long rigid and infrangible structure providing an unusually long flexible wheel base, having in combination therewith a plurality of pivotal supporting trucks located at or near the extremities of said structure, one of the said trucks provided with driving mechanism.

4. In a locomotive a boiler, tender and interposed cab between them, connected to each other and to a supporting frame so as to form an unusually long rigid and infrangible structure, having in combination therewith a plurality of supporting pivotal driving trucks fitted with side bumpers at one end of the said trucks.

5. In a locomotive a boiler, tender and interposed cab between them, connected to each other and to a supporting frame so as to form an unusually long rigid and infrangible structure, having in combination therewith a plurality of supporting pivotal trucks, the rear one of said trucks fitted with driving mechanism while the leading truck is provided with free wheels, both of said trucks fitted with side bumpers.

6. In a locomotive a boiler, tender and interposed cab between them, connected to each other and to a supporting frame so as to form an unusually long rigid and infrangible structure providing an extended wheel base, having in combination therewith a reversible leading free wheeled pivotal truck.

7. In a locomotive a boiler, tender and interposed cab between them, connected to each other and to a supporting frame so as to form an unusually long rigid and infrangible structure, having in combination therewith a reversible leading free wheeled pivotal truck fitted with side bumpers at each end of the rigid frame-work of the said truck.

8. The combination with a boiler and tender forming with the underframe a rigid, unitary structure, the underframe being extended beyond the common length, of driving trucks only having cylinders, and pivoted to the said frame near its ends to furnish a wheel base of unusually great length and thereby providing great fire-box space, the said trucks being also supplied with bumpers.

9. The combination with a boiler and tender forming with the underframe a rigid, unitary structure, the underframe being extended beyond the common length, of a plu-

rality of driving and supporting, pivotal trucks near its ends to furnish a wheel base of great length and great fire-box space, the said trucks being also supplied with bumpers.

5 10. The combination with the forward end of the boiler and the extended frame of a bolster provided with a forwardly extended base and interposed between them.

In testimony whereof I have hereunto set my hand in presence of two subscribing wit- 10 nesses.

THOMAS H. BRIGG.
